Primary Examiner — Cynthia Ramirez*Assistant Examiner* — Michael A Maharajh(74) *Attorney, Agent, or Firm* — Inventech Patent Services, LLC; Marc A. Scharich(57) **CLAIM**

I claim the ornamental design for a massage roller, as shown and described.

DESCRIPTION

FIG. 1 is a perspective view of a massage roller, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-end elevational view thereof; and,

FIG. 7 is a right-end elevational view thereof.

The broken lines shown in the drawings are included for purposes of illustrating portions of the massage roller and form no part of the claimed design.
